RADIOCHEMICAL TREATMENT OF HEAVY OILS

Barry L. Tarmy, Cranford, and Robert B. Long, Wana-

massa, N.J., assignors to Esso Research and Engineer-

ing Company, a corporation of Delaware

Application June 21, 1956, Serial No. 592,983

4 Claims. (Cl. 204—154)

This invention relates to radiochemical treatment of hydrocarbon oils. It is particularly concerned with the treatment of heavy hydrocarbon oils by high intensity ionizing radiation, preferably gamma rays, to prevent or greatly reduce the formation of water-oil emulsions on subsequent water washing of the heavy oil or treatment with an aqueous medium.

In brief compass, this invention proposes a process of treating petroleum fractions containing a substantial proportion of constituents non-vaporizable at atmospheric pressure without cracking, which comprises irradiating such a fraction with high intensity ionizing radiation, to the extent that the fraction receives a dosage in the range of 10 to 10^3 megaroentgens, and then washing the fraction so treated with water. The temperature of treatment is preferably under 500° F., and the conditions are such that less than 5 wt. percent of the oil is converted to C₃-materials, including coke.

This invention is concerned with oils that contain an appreciable amount of heavy material such as asphaltenes, naphthenic acids, and the like, that result in the formation of water-oil emulsions. For the purpose of this invention, such heavy oils are defined as oils containing at least 5% of constituents non-vaporizable at atmospheric pressure without cracking, and include whole crudes, residua therefrom, shale oil, coal tars, asphalts, and similar materials.

In many cases it is desirable to treat heavy oils with water or an aqueous medium to remove salts or similar contaminants. With many oils, the heavier portions are responsible for forming stable water-oil emulsions. Severe and repeated treatments may be required to break these emulsions.

It has now been found that when a heavy oil is sufficiently irradiated, especially with gamma rays prior to treatment with water, the tendency of the oil to form water-oil emulsions is at least substantially reduced, if not eliminated. An important feature of this invention is that only a relatively small dosage is required to achieve this effect, compared to other types of hydrocarbon radiochemical reactions.

The following description of the drawing attached to and forming a part of this specification will serve to make this invention clear.

As illustrated, a heavy hydrocarbon oil from source 1 is introduced into a radiation reaction zone 2 by line 3. The irradiation, including charged particles and photons, provided in radiation source 2 can be obtained from artificial accelerators, nuclear waste products, or products especially made radioactive by insertion in nuclear reactors such as cobalt 60, the use of radio-isotopes being preferred. In this preferred form of the invention, the average gamma ray flux in the reaction zone is better than 10^5 Roentgens/hr. It is also preferred that the conditions be such that the heavy hydrocarbon oil receive a dosage of 10 to 10^3 megaroentgens. The material is exposed to the radiation source simply by flowing it in pipes past or through the radioactive material.

2

A nuclear reactor such as an atomic pile can be the radiation source. Generally speaking, a much higher level of irradiation is obtainable and thus the irradiation times can be reduced. In this embodiment of the invention, besides the above level of gamma ray flux, it is preferred that the neutron flux at the point of irradiation be above about 10^8 neutrons/cm.²/sec. The total radiation dosage is maintained in the range of 36 to 3600 B.t.u.'s/lb.

10 When using a nuclear reactor, the heavy oil is simply pumped through pipes disposed in or around the fissionable material. Heterogeneous or homogeneous reactors can be used. Conventional moderators such as carbon, light and heavy water, or hydrocarbons can be used to control the energy of the neutrons. In some cases the hydrocarbon reactant can serve as a moderator.

The temperature during irradiation is generally below thermal conversion temperatures, i.e., below 700° F., preferably below 500° F. While high pressures can be

20 used, the pressure usually is in the range of 0 to 50 p.s.i.g. The time of treatment to receive the above dosages is normally in the range of 0.01 to 5000 min. Conversion of the oil is maintained below 5 wt. percent to C₃'s, C₂'s, methane, hydrogen, and coke.

25 After this irradiation treatment, the heavy oil is admixed, if desired, with a suitable organic solvent such as benzene, pyridine, phenols, glycols, resorcinols, and mixtures thereof, supplied from source 4, by line 5. Then it is treated with water supplied by line 6 from

30 source 7 to remove salts, metals, and other contaminants, and passed to zone 8. Customary water washing techniques are used in zone 8. The amount of water used varies from 0.5 to 10 lbs./lb. of heavy oil. Conventional pressures and temperatures are used, e.g., 0 to 400 p.s.i.g., and 60 to 400° F. This water washing zone can, of course, consist of several stages or can operate counter-currently in manners well known in the art.

During the water washing, well known materials, here called extraction aids, supplied by line 9 from source 10, can be used to facilitate the removal of the contaminants and other materials. These extraction aids include, for example, strong inorganic acids such as HCl, H₂SO₄, H₃PO₄, H₂S, and hypochlorites.

After the water treatment, the treated heavy oil is passed by line 11 to separation zone 12, here shown as being separate from zone 8, but separation can, of course, occur in zone 8. If a separate separation stage is used, this can include well known separating means such as settling, stripping, distillation, adsorption and absorption. The recovered aqueous medium, solvent and/or extraction aid is removed by line 13 and can be recycled if desired. The treated heavy oil is removed by line 14.

Example

55 900+° F. Bachaquero residua was subjected to 120 megaroentgens of gamma irradiation at 110° F., and 16.7 megaroentgens at temperatures of 450° and 650° F. The samples were then dissolved in benzene and treated with water, aqueous pyridine and dilute HCl. The samples were easily washed with the aqueous medium without any water emulsions being formed. In contrast, the original feed and the feed that was subjected to elevated temperatures for the same length of time without radiation, formed stable emulsions which required hydrochloric acid and repeated heat shock treatment to be broken. Even with these treatments, it was not possible to completely remove all the water in the non-irradiated samples.

60 More particularly, the Bachaquero residua had the following inspections: boiling point 900° F.+, sulfur 3.26 wt. percent, modified naphtha insolubles 18.2 wt. percent, and specific gravity 1.022.

The samples were irradiated by exposure to a cobalt 60 source having a strength of about 3100 curies. Two 500 ml. bombs, one containing 403 gr. and the other 396 gr. of Bachaquero residuum, were placed at a distance of about 4½ inches from the cobalt 60 source and heated to 450° F. and 650° F. respectively for 116 hours at a gamma dose rate of about 144,000 Roentgens/hr. Simultaneously a 143 gr. sample was placed in the high intensity center of the cobalt 60 source, absorbing gamma radiation at a rate of about 1.03×10^6 Roentgens/hr. at an ambient temperature of about 120° F. A line led from each bomb to a knockout trap to catch any liquid that might come over, and then to a gas meter and sample bomb. Duplicate runs were also made without radiation. All radiation runs produced some gas, while substantially no gas was obtained without radiation. During the 650° F. run, some liquid was obtained in the knockout trap.

The irradiated samples were first dissolved in benzene (2 parts benzene—1 part residuum) to obtain a liquid that would flow easily. The samples were then washed with water (5 parts total water to 1 part residuum solution). The irradiated samples did not emulsify while the non-irradiated samples did. The samples were further treated with HCl and pyridine, and filtered. The emulsions from the non-irradiated samples were almost completely, but not quite, broken with a repeated heat-shock and HCl treatment.

Having described the invention, what is sought to be protected by Letters Patent is succinctly set forth in the following claims.

What is claimed is:

1. A process for pretreating a heavy petroleum oil con-

taining a substantial proportion of constituents non-vaporizable at atmospheric pressure without cracking, whereby the propensity of the heavy petroleum oil to form stable emulsions when subsequently treated with an aqueous medium is substantially reduced, which comprises irradiating said heavy petroleum oil with gamma radiation to a total dose in the range of 10 to 10^3 megarontgens, and under conditions such that less than 5 weight percent of said heavy petroleum oil is converted to C_3 's, C_2 's, methane, hydrogen and coke, and then contacting the heavy oil so treated with an aqueous medium.

2. The process of claim 1 wherein said radiation is obtained from a radio-isotope.

3. The process of claim 1 wherein the temperature during irradiation is maintained below 500° F.

4. The process of claim 1 wherein said oil after irradiation is first admixed with an organic solvent.
